UNITED STATES PATENT OFFICE.

OTTO WIRZ, OF CANNSTATT, GERMANY, ASSIGNOR TO THE FIRM: CANNSTATTER MISCH- UND KNETMASCHINENFABRIK CANNSTATTER DAMPFBACKOFENFABRIK, WERNER & PFLEIDERER, OF CANNSTATT, GERMANY.

HYDRAULIC ACCUMULATOR.

Application filed April 26, 1924. Serial No. 709,299.

To all whom it may concern:

Be it known that I, OTTO WIRZ, a citizen of Switzerland, residing at Cannstatt, Germany, have invented certain new and useful Improvements in Hydraulic Accumulators, of which the following is a specification.

My invention refers to hydraulic accumulators and more particularly to devices of the sort in which a piston is arranged for free reciprocation within a cylinder, means being provided for supplying water under pressure below the piston, while the cylinder space above the piston is filled 10 with air. In accumulators of this type, the piston has been connected with a rod extending through the bottom of the cylinder by means of a non-rigid connection, such as a number of telescoping sleeves, this 15 rod serving for actuating the means for regulating the supply of water to the cylinder.

It is an object of my invention to improve more particularly the operative connection 20 between this rod and the liquid supply regulating means with a view to providing a particularly simple and effective means of exactly adjusting the liquid supply.

In the drawings affixed to this specification and forming part thereof, two modifications of a device embodying my invention are illustrated diagrammatically by way of example. In the drawings—

Figs. 1 and 2 illustrate the first modification,

Fig. 1 being an axial section of the hydraulic cylinder, the other parts being shown in elevation, while

Fig. 2 is an elevation, partly in section, 40 of the lower end of the rod and the parts connected therewith.

Figs. 3 and 4 illustrate a second modification,

Fig. 3 being a view similar to the lower 45 portion of Fig. 1, while

Fig. 4 is a plan view of the parts shown in the lower half of Fig. 3.

Referring first to Figs. 1 and 2, *a* is the liquid and *b* is the air space adjoining the 50 two faces of the piston *c* which is arranged

for free reciprocation within the accumulator cylinder *d*. *e*, *e* are a number of telescoping sleeves, the uppermost of which is fixed to piston *c* and which are provided with flanges *f* preventing the single sleeves from being disengaged from one another. *g* is the piston rod extending into the lowermost sleeve *e* held therein by its enlarged head *h*.

The lower end of rod *g* is enlarged to 60 form a foot *i* surrounded by a tubular slide *m* suspended in a ring *p* connected by links *q* to the lower ends of a fork forming part of the counter-weighted double-armed lever *k*. The tubular slide *m* is closed at its upper end by a cap *o* leaving a passage for the rod *g* and at its lower end by a bottom *n*. The slide *m* is freely suspended in ring *p* and in its lowermost position rests on the ring with the lower edge of the cap *o*. On 65 the slide *m* there is adjustably mounted a catch *r*.

A forked bell crank lever *s* embraces slide *m*, its upwardly directed arm has a hook-shaped catch *t* cooperating with a 70 cross beam *u* inserted in the fork of the weighted lever *k*, so as to lock this latter in one of its end positions, where the pump (not shown) which forces liquid into the cylinder *d* is operating.

On the pivot pin *v* of lever *k* a cam *w* is mounted which cooperates with a lever *y* turning about point *x* and connected with the rod *z* of the distributing valve (not shown) which, when rod *z* is in its uppermost position, connects the suction chamber and the pressure chamber of the pump, while in the opposite position of rod *z* the valve separates these chambers.

According as catch *r* is adjusted in higher or lower position on slide *m*, the pump is thrown out sooner or later and consequently the stroke of piston *c* is increased or decreased, the pressure available in the accumulator being varied accordingly.

In the operation of the device, the accumulator is charged by the pump forcing water into the space below the piston *c* which is thereby caused to rise, the telescoping sleeves *e*, *e* being drawn asunder 100

until the flange *f* of the lowermost sleeve carries the head *k* of rod *g* along. The feet *i* of this rod will move upwards in the tubular slide *m* until it meets the cap *o*, whereupon slide *m* will rise in ring *p* together with rod *g* until catch *r* meets the forked ends of bell crank lever *s* which is thereby caused to rock about its pivot. The hook *t* being disengaged from cross-beam 10 *u* of lever *k*, this latter is now caused by its counter weight to assume the position shown in dotted lines. At the same time, cam *w* lifts lever *y* which acts towards opening the distributing valve, whereby the 15 pump is caused to run idle. Upon liquid under pressure being allowed to escape from cylinder *d*, piston *c* will descend and rod *g* will move in downward direction, until it reaches the position shown in Fig. 1. 20 Near the lower end of its stroke, the foot *i* meets the bottom *n* of slide *m*, carrying this latter along with it until cap *o* meets ring *p*, whereby lever *k* is moved back into the position shown in full lines. At the 25 same time, ring *p*, pressing the forked end of bell crank lever *s* downwards, causes hook *t* to engage cross-beam *u*, thereby locking lever *k* in its end position. At the same time, cam *w* moves back into its initial 30 position, whereby lever *y* is enabled to lift rod *z*, thereby closing the valve and allowing the pump to force fresh liquid into the 35 accumulator.

In the modification illustrated in Figs. 3 and 4, the slide *m* is mounted for vertical reciprocation in a suitable guide 1 and carries a rack 2 meshing with a gear 3 mounted on an axle *v'*. The hub 4 of gear wheel 3 forms one half of a clutch, the other half of 40 which forms part of the hub 5 of weighted lever *k'*, which is mounted on axle *v'* for free rotation, being secured, however against axial motion. A cam, eccentric or the like *w'* mounted on axle *v'* acts on lever *y* and rod *z* of the valve.

According as one or the other tooth of gear wheel 3 and rack 2 are in gear with one another, and in accordance with the diameter of gear wheel 3 and the width of the tooth 50 gaps of clutch 5, the rocking motion of lever *k* will take place in shorter or longer periods and in accordance therewith the stroke of the piston in the cylinder *d* and the pressure in the accumulator will vary. On the accumulator being charged with liquid, the foot of rod *g* will carry slide *m* upwards, together with rack 2. Gear wheel 3 being turned thereby, causes lever *k'* to be rocked into the opposite position. In this movement, the 55 lever *k'*, being coupled with shaft *v'* by aid of clutch 4, 5, causes cam *w'* to lift lever *y* and to thereby change the operative position of the valve. On pressure liquid being 60 tapped from cylinder *b*, rod *g* will act on

sleeve *m*, thereby depressing rack 2, whereby gear wheel 3, axle *v'* and lever *k'* are turned in opposite direction, whereby cam *w'* is withdrawn from underneath lever *y*, whereby the valve is closed and the pump is started.

I wish it to be understood that I do not desire to be limited to the exact details of construction shown and described, for obvious modifications will occur to a person skilled in the art.

I claim:—

1. Hydraulic accumulator comprising a closed cylinder, a piston freely reciprocable in said cylinder, a piston rod movably extending through the bottom of said cylinder, a non-rigid connection between said piston and said piston rod, a slide movable on the free part of said rod, means for limiting the range of movement of said slide relatively to said rod, a distributing valve adapted to govern the supply of liquid to said cylinder, a lever adapted to control the operative position of said valve and adjustable means connected with said slide and arranged to act on said lever.

2. Hydraulic accumulator comprising a closed cylinder, a piston freely reciprocable in said cylinder, a piston rod movably extending through the bottom of said cylinder, a non-rigid connection between said piston and said piston rod, a slide movable on the free part of said rod, means for limiting the range of movement of said slide relatively to said rod, a distributing valve adapted to govern the supply of liquid to said cylinder, a lever adapted to control the operative position of said valve, means for locking said lever and adjustable means connected with said slide and arranged for changing the operative position of said locking means and of said lever.

3. Hydraulic accumulator comprising a closed cylinder, a piston freely reciprocable in said cylinder, a piston rod movably extending through the bottom of said cylinder, a non-rigid connection between said piston and said piston rod, a slide movable on the free part of said rod, means for limiting the range of movement of said slide relatively to said rod, a distributing valve adapted to govern the supply of liquid to said cylinder, a weighted lever adapted to suddenly reverse the operative position of said valve and adjustable means connected with said slide and arranged to act on said lever.

4. Hydraulic accumulator comprising a closed cylinder, a piston freely reciprocable in said cylinder, a piston rod movably extending through the bottom of said cylinder, a non-rigid connection between said piston and said piston rod, a slide movable on the free part of said rod, means for limiting the range of movement of said slide relatively

to said rod, a distributing valve adapted to govern the supply of liquid to said cylinder, a weighted lever adapted to suddenly reverse the operative position of said valve, a double-armed lever connected with said valve, a cam connected with said weighted lever arranged to act on the free end of said double-armed lever and adjustable means connected with said slide and arranged to act on said weighted lever. 10
In testimony whereof I affix my signature.

OTTO WIRZ.
